UNITED STATES PATENT OFFICE.

JOHN D. COLBY, OF LOWELL, MASSACHUSETTS.

SPINDLE-BOLSTER FOR SPINNING-MACHINES.

SPECIFICATION forming part of Letters Patent No. 342,581, dated May 25, 1886.

Application filed August 18, 1885. Serial No. 174,679. (No model.)

To all whom it may concern:

Be it known that I, JOHN D. COLBY, of Lowell, in the county of Middlesex, Massachusetts, have invented certain new and useful Improvements in Spindle-Bolsters for Spinning-Machines, of which the following is a specification.

The objects of my invention are to simplify and lessen the cost of construction of the devices in question, to more effectively lubricate the spindle, and so construct and support the spindle and bolster bearing that the former may be run at high speed without vibration.

My invention can best be understood by reference to the accompanying drawings, in which I have shown a means for carrying it into effect.

Figure 1 is a vertical section of a bobbin-spindle and bolster embodying my invention. Fig. 2 is a perspective view of a section of the bolster and supporting parts.

Referring to the drawings, A indicates a portion of the rail of a spindle-frame, B a spindle adapted to be rotated by the whirl C, which is attached thereto, and D the bobbin carried by the spindle. The bearing for the spindle is furnished by the bolster tube E, and a step to properly support the lower end of the spindle is also provided, preferably by inserting in the lower end of the bolster E a vertically-adjustable plug, e. The bolster is supported by a surrounding tube, F, of greater diameter, with which it is connected by a thin horizontal web, f. I prefer to connect the web f with the bolster E at about the middle of the latter, and to place the whirl C, carried by a downwardly-extending sleeve, C', in substantially the same horizontal plane as the web. It will be seen that by this arrangement, while the bolster at its upper and lower ends may be somewhat deflected from the axis of the supporting-tube F, and thus accommodate itself to the spindle, the web f forms at the center of resistance of the bolster a bearing which is unyielding laterally, so that the bolster as a whole does not change its position in the least; also that the lateral strain exerted by the whirl C is directly in line with the immovable por-

tion of the bolster E, and therefore does not affect the yielding action of the bolster.

I prefer to construct the supporting-tube F, bolster E, and web f in one piece, the annular chambers G and H being formed in casting or bored out. The attachment of these parts to the rail A may be effected by a screw, I, which passes through the rail and engages with the supporting-tube F.

I prefer to make the screw I with a chamber, i, to receive lower end of the bolster. Besides thus enabling the latter to be made of greater length, and to extend down to or below the upper side of the rail A, making the device more compact, an oil-cup is provided for lubricating the lower end of the spindle. This is effected through a hole, e', in the lower end of the bolster. The oil entering the bolster by the hole e' is carried around and up by the action of the spindle, and overflows from the upper end of the bolster E into the chamber G; thence it passes through perforations in the web f into the lower chamber, H, and cup i again, thus effecting a constant and thorough lubrication of the spindle.

To prevent the oil, as it issues from the upper end of the bolster, from being forced over the top and onto the outside of the tube F, I provide the spindle with a flange or collar, b.

The spindle B may fit the tube E for the whole length of the latter, or it may be tapered more than the said tube, and fit the latter only at its upper end, thus giving the lower end of the spindle some freedom of lateral movement on the step.

The mode of operation of the device has been already sufficiently indicated.

What I claim is—

1. A supporting-tube and a bolster-tube connected by a thin transverse web, substantially as set forth.

2. A supporting-tube and a bolster-tube connected by a transverse web at the middle of the bolster-tube, substantially as set forth.

3. A supporting-tube and a bolster-tube formed in one piece and connected by the transverse web f, substantially as set forth.

4. The combination, with the spindle, of a

supporting-tube and bolster-tube connected by a transverse web and a whirl attached to the spindle and situated substantially in the plane of the web, as set forth.

5 5. A supporting-tube and a bolster-tube connected by the web *f*, the bolster-tube being provided with the adjustable step *e* in the lower end thereof, substantially as set forth.

6. A supporting-tube and a bolster-tube connected by the transverse web *f*, in combination

with the screw *I*, adapted to engage with the supporting-tube, and having the chamber *i*, substantially as set forth.

In testimony whereof I have hereunto set my hand this 12th day of August, 1885.

JOHN D. COLBY.
